[57] **CLAIM**

The ornamental design for a corner style pet feeding station, as shown and described.

DESCRIPTION

FIG. 1 is a front perspective view showing my new design for a corner style pet feeding station;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof;

FIG. 8 is a front perspective view of a modified form of the corner style pet feeding station shown in FIG. 1;

FIG. 9 is a top plan view of FIG. 8;

FIG. 10 is a bottom plan view of FIG. 8;

FIG. 11 is a front elevational view of FIG. 8;

FIG. 12 is a rear elevational view of FIG. 8;

FIG. 13 is a left side elevational view of FIG. 8; and,

FIG. 14 is a right side elevational view of FIG. 8.
